FUEL ATOMIZING DEVICE

John H. Huss, New York, N. Y., assignor to Henry Huss, Port Chester, N. Y.

Application January 28, 1944, Serial No. 520,054

7 Claims. (Cl. 299—143)

My invention is directed to an improved fuel atomizing device.

One of the objects of my device is to provide a fuel atomizing device whereby not only is good atomization of the fuel obtained, but by employing a plurality of cooperating nozzles or groups of nozzles I obtain the very much desired control of the shape and direction of the flame resulting from the combustion of the fuel being handled.

Another object of my invention is to provide a fuel atomizing device wherein although I employ a plurality of cooperating nozzles a wide range of discharge is obtained by simple valve manipulation.

My invention also provides a device with which heavy oil is easily atomized, inasmuch as there is a straight, through flow for the oil, as distinguished from present day practice wherein oil nozzles are equipped with tangential slots which set up rotation in the oil.

Still another object of the invention is to provide a construction embodying groups of nozzles so that several different types of oil may be atomized at the one time and combined so as to form a single flame, thereby insuring a high degree of combustion.

By employing groups of nozzles which may or may not be of the same design, I am able to obtain various shapes of flame so as to obtain high efficiency with combustion chambers of varying shapes and capacity.

The nibs, that is, the members through which the oil or other fuel discharges directly, are readily changed when desired to vary the amount of fuel which is atomized.

Other objects of the invention will appear hereinafter.

In the accompanying drawings:

Fig. 1 is a longitudinal sectional elevational view of an embodiment of my invention;

Fig. 2 is a fragmentary sectional view on the line 2—2 of Fig. 1;

Fig. 3 is an end view of the nozzles or nibs;

Fig. 4 is a section taken on the line 4—4 of Fig. 2;

Fig. 5 is a part sectional elevational view of another embodiment of the invention;

Fig. 6 is a part sectional elevational view of still another embodiment of the invention;

Fig. 7 shows in part sectional elevation a further embodiment of the invention wherein several pairs of nozzles are independently controlled;

Fig. 8 is an end view of Fig. 7; and

Fig. 9 is a section on the line 9—9 of Fig. 7.

Referring to the drawings in detail and first of

all to Figs. 1 to 4, inclusive: 2 designates the fuel supply line, 4 the feed tube and 6 the nozzle body. The fuel supply line is of course connected to the feed tube, as illustrated, and is controlled by valve 8.

The nozzle body 6 is screwed upon the discharge end of the feed tube 4 and is provided centrally with fuel passageway 10, and at opposite sides of this passageway with fuel passageways 12. The passageways 12 are diametrically opposite each other and precisely in line with the center of fuel passageway 10.

Mounted in the outer end of the nozzle body 6 are two pairs or groups of nozzles 14 and 16.

Each of the nozzles 14 is provided with a longitudinally extending fuel passage or bore 18 extending completely through the nozzle, the inner end of each of these bores communicating at all times with central fuel passage 10. Each nozzle 14 additionally is provided with a cross fuel passage 20 extending completely through the nozzle, at a 45° or other angle desired to the longitudinal axis of the nozzle body 6. The inner end of each of the fuel passages or bores 20, that is, the end nearest the longitudinal axis of the nozzle body, is provided with tip or nib 22. These tips or nibs are held in place by a threaded cap washer 24. The outer ends of each of the fuel passages 18 and 20 are closed by caps 26 and washers 28.

30 This is a very excellent construction, in that it permits the nozzles to be cleaned with the minimum of effort, and also permits the nibs 22 to be cleaned or changed whenever desired.

The two nozzles 16 are similar in construction to the nozzles 14, so that it will be unnecessary to describe them in detail. It should be noted, however, that the fuel passage 18 of one of these nozzles is in constant communication with one of the side bores 12, while the passage 18 of the other nozzle is in constant communication with the other of the side bores 12.

45 The inner end of the central fuel passage 10 is provided with a needle valve 30, which extends lengthwise of the feed tube 4 and is controlled by wheel 32.

It has already been pointed out that the fuel is supplied to the nozzle groups through valve controlled supply line 2. This line is in direct communication with the feed tube 4, and the nozzles 16 are in constant communication with this tube by way of bores 18. Consequently any adjustment of the valve 8 in the supply line 2 varies conditions at the nibs of this nozzle group. On the other hand, while the bore or fuel passage 18 is in communication with the feed tube 4, this

bore is valve controlled by needle valve 30, so that by manipulation of the two valves 8 and 30 one obtains very flexible control of flame conditions at the discharge end of the equipment, so as not only to obtain most efficient combustion but by varying the flame shape the equipment is capable of use at very high efficiency in combustion chambers of different dimensions as well as shapes.

It will be appreciated from the foregoing that in laying out the nozzle arrangement care is exercised to insure that the fuel streams will impinge upon each other with great accuracy. It will be appreciated also that while I have shown the nozzles set at a 45° angle to the longitudinal axis of the feed tube, this angle may be varied as desired.

It is to be understood too that I have shown two groups of nozzles merely for descriptive purposes. This number may be increased as may be desired without departing from the spirit and scope of my invention. I have found, however, with but two groups of nozzles I not only obtain excellent atomization of the fuel, but, which is of equal and even of major importance so far as my invention is concerned, I obtain excellent control of the atomized fuel and hence of the flame as the fuel is burned. It is essential to my invention that the fuel after atomization be controlled in that controlled atomization is the desideratum rather than the mere release of atomized fuel into a combustion chamber.

Referring to the embodiment of the invention as illustrated in Fig. 5, the fuel supply line is designated 2 and the feed tube is designated 4, while the supply of fuel to the feed tube is controlled by the valve 8.

As in Fig. 1, the nozzle body 6 is screwed upon the feed tube and carries pairs or groups of nozzles 14 and 16. These nozzles are of the same construction as those of Fig. 1, and hence it is unnecessary to describe them in detail.

In this embodiment of the invention I have omitted the needle valve 30 of Fig. 1, retaining, however, the feature of having several nozzles all mounted in the same head and so disposed that the fuel streams will impinge upon each other. By regulating the valve 8 the desired control of the atomized fuel is obtained.

In the embodiment of my invention as illustrated in Fig. 6 I provide an outer feed tube 36, carrying nozzle body 6. As in the other embodiments of the invention illustrated the nozzle body carries nozzle groups 14 and 16. It is to be noted, however, that in this embodiment of my invention only the nozzles 14 are in communication with the feed tube 36. The fuel supply to this tube and hence to the nozzles 14 is controlled by valve 38.

Extending through the feed tube 36 is another feed tube 40, the fuel passing therethrough being controlled by valve 42. The inner end of this tube is screwed into an internal projection or boss which is integral with the nozzle body 6, and which communicates only with the nozzle group 16. The internal construction of the nozzles 14 and 16 may be the same as Fig. 1. It is to be noted, however, that nozzle group 14 is controlled by valve 38, while group 16 is controlled by valve 42, each group independently of the other. This permits two different fuels to be employed at the same time, which is of considerable advantage in that by utilizing two different types of fuel

in one flame a high degree of combustion is obtained.

For example, I may burn a very high flashpoint oil, which is ordinarily quite difficult, by feeding this high flashpoint fuel through one nozzle group while feeding low flashpoint fuel through the other group.

Referring to Figs. 7, 8 and 9: In this embodiment of my invention I have provided a further refinement of my invention, in that I have provided three groups of nozzles with a separate control for each group.

36 designates an outer feed tube mounting the nozzle body 6 which in this construction carries three groups or pairs of nozzles, 50, 52 and 54, and the feeding of fuel to any group is independent of the feeding of fuel to the other groups.

It will be apparent from Figs. 7 and 9 that the nozzle body 6 is bored as illustrated at 56 so as to provide fuel ducts communicating with feed tube 36 and nozzle group 50. The fuel feed to feed tube 36 is controlled by valve 38.

Extending along the interior of the feed tube 36 is a second feed tube 58. This tube is out of communication with the feed tube 36, and is controlled by valve 60. The inner end of this tube communicates with a central bore 61 in the nozzle body 6, this bore in turn communicating with fuel bores 62 leading to the nozzles 52.

Intermediate the feed tubes 36 and 58 is a third feed tube 64, controlled by valve 66. This tube is out of communication with feed tubes 36 and 58, but at its inner end constantly communicates with ducts 68 leading to nozzles 54.

The nozzles 50, 52 and 54 may be similar in construction to the nozzles of Fig. 1, so that it becomes unnecessary to illustrate and describe them in any detail.

It will be seen that in this embodiment of my invention I provide three groups of nozzles each independently controllable so that excellent control of combustion is obtained, even more refined than the construction of Fig. 6.

It will be appreciated that the nozzles are so set as to incline toward each other to effect impingement of the fuel streams upon each other.

I wish it to be understood that changes may be effected in the details of construction and arrangement of parts hereinabove described without departing from the spirit and scope of my invention.

What I claim is:

1. A fuel atomizing device comprising in combination a feed tube, a nozzle body carried at the inner end of the feed tube, pairs of nozzles branching from the nozzle body and so positioned that the fuel streams discharged from the various nozzles will impinge upon each other, and valve mechanism for varying the amount of fuel supplied to one pair of nozzles without varying the fuel supplied to the other nozzles.

2. A fuel atomizing device comprising in combination a feed tube, a nozzle body carried at one end thereof, a plurality of pairs of nozzles branching from said body and all directed toward a common focal point whereby the fuel streams from the several nozzles will impinge upon each other, and valve mechanism for varying the amount of fuel supplied from the feed tube to one pair of nozzles without varying the fuel being supplied to the other nozzles.

3. A fuel atomizing device comprising in combination a fuel feed tube, a nozzle body carried

at one end thereof, a plurality of nozzles branching therefrom, said nozzles being so disposed that fuel streams issuing therefrom all converge to a common point, passages in said nozzle body for conducting fuel directly from the feed tube to some of said nozzles, and valve controlled fuel passages for conducting fuel from the feed tube to the others of said nozzles.

4. A fuel atomizing device comprising in combination a nozzle body, a plurality of nozzle groups carried thereby, a fuel feed tube for supplying fuel to one group of nozzles, and a second tube within the first tube for supplying fuel to the other nozzle group, said nozzles all being directed toward a common focal point whereby the fuel streams will impinge upon each other, and a valve for each feed tube.

5. A fuel atomizing device comprising in combination a nozzle body, a feed tube carrying said body, a group of nozzles carried by the nozzle body and communicating with said feed tube, a valve for controlling the fuel passing through said feed tube, a second group of nozzles carried by said nozzle body and out of communication with said feed tube, a second feed tube extending through the first feed tube for supplying fuel to the second nozzle group, a valve for controlling said second feed tube independently of the fuel passing through the first mentioned feed tube, all of said nozzles being inclined toward each other and directed toward a common focal point

whereby the fuel streams issuing from the nozzles will impinge upon each other.

6. A fuel atomizing device comprising in combination a nozzle body, a plurality of nozzles carried thereby, a fuel feed tube connected to a fuel supply for supplying fuel to some of said nozzles, a second fuel feed tube connected to another fuel supply for supplying fuel to others of said nozzles, a separate valve for each tube, a longitudinal fuel passage in each nozzle accessible for cleaning from the nozzle exterior and communicating with the feed tube for the nozzle, a transverse fuel passage in each nozzle intersecting the said longitudinal fuel passage, said transverse passages being accessible for cleaning from the nozzle exterior, and a removable nib in the discharge end of each transverse fuel passage, said transverse fuel passages being so disposed that fuel streams issuing therefrom all converge to a common point.

7. A fuel atomizing device comprising in combination a nozzle body, a plurality of nozzles carried thereby, a fuel feed tube connected to a fuel supply for supplying fuel to some of said nozzles, another fuel feed tube connected to another fuel supply for supplying fuel to others of said nozzles, said nozzles all being directed toward a common focal point, and a separate valve for each feed tube.

JOHN H. HUSS.
